SAFETY SWITCH POINT BRIDAL BAR
PROTECTOR

Andrew M. Ritchey, San Antonio, Tex.

Application December 27, 1939, Serial No. 311,181

4 Claims. (Cl. 246—452)

This invention relates to a safety switch point bridal bar protector.

An object of the invention is the provision of safety means whereby repair men are able to detect imperfect condition of the switch to eliminate accident.

Another object of the invention is to provide an attachment to hold the switch point in position against the stock rail in the event of a break 10 in the bridal bar or bridal bar connections.

A further object of the invention is to provide an attachment that will give additional strength and security of the switch point's position against the stock rail in the event a break occurs 15 which often does in the bridal bar or bridal bar connections.

Another object of the invention is the construction of a switch attachment which will operate efficiently, and can be constructed at a minimum 20 cost.

A still further object of the invention is the construction of a switch mechanism which will afford easy inspection, whereby any broken part will be readily discovered, and by the efficient 25 and simple nature of the mechanism the same can be efficiently and quickly repaired.

With the foregoing and other objects in view, the invention comprises certain novel constructions, combinations and arrangements of parts 30 as will be hereinafter fully described, illustrated in the accompanying drawings, and more particularly pointed out in the appended claims.

In the drawings:

Figure 1 is a top plan view of a closed switch 35 mechanism constructed in accordance with the present invention, while

Figure 2 is a fragmentary plan view showing the same in an open position.

Figure 3 is an enlarged sectional view taken 40 on line 3—3, Fig. 2, and looking in the direction of the arrows.

Figure 4 is an enlarged plan view of the switch-point rods and the yoke device.

Figure 5 is an enlarged sectional view taken 45 on line 5—5, Fig. 2, and looking in the direction of the arrows.

Figure 6 is an enlarged sectional view taken on line 6—6, Fig. 1, and looking in the direction of the arrows.

50 Referring to the drawings, in which I have shown the preferred embodiment of my invention, 1 designates the standard rails and 2 and 3 are the movably mounted switch-points. A bridal bar 4 extends under the rails and switch-points, and on bar 4 are two similarly constructed fas-

tening devices 5. Each fastening device 5 comprises a body 6, in which are a plurality of aligned apertures 7. In one of the apertures 7 is a bolt 8 that extends through the bridal bar 4, fastening device 5 thereto. The device 5 is provided with a flange 9 against the switch-point and bolts or similar fastening means 10 secure said flange 9 to the switch-point.

A connecting rod 11 is pivotally secured at 12 to the inner end of the bridal bar 4; the outer end of rod 11 is movably connected in any suitable manner to the vertical shaft 13, to which shaft is suitably secured handle 14. Therefore, when handle 14 is operated rod 11 will be moved horizontally, imparting similar movement to the 15 bridal bar 4 and switch-points 2 and 3.

A yoke device 15 is mounted upon connecting rod 11. This yoke device (Fig. 5) comprises an upper flat primary plate 16, which plate 16 is provided at its ends or side edges with integral 20 sleeves 17. An auxiliary plate 18 is provided with flat flanges 19; these flanges 19 rest flat against the inner face of primary plate 16, between the sleeves 17. Vertical bolts 20 extend through the flanges 19 and through the primary plate 16, with 25 their heads between the sleeves 17 and the sleeve-like body 21 of the auxiliary plate 18, with their upper threaded ends carrying nuts 22, through which nuts and bolts extend cotter pins 23. The connecting rod 11 is in the sleeve-like body 30 21 of the auxiliary plate 18.

Switch-point rods 24 extend through sleeves 17; these rods are spread laterally outwardly at 25, and each rod is provided on its outer end with a hook 26. The hooks 26 engage the flange 27 35 of the switch-point 2. The portion of each rod 22 that is in the sleeve 17 is externally screw threaded; this screw threaded portion extends beyond opposite ends of each sleeve, and upon these threaded portions are mounted lock nuts 28, 40 whereby the rods can be adjusted accurately upon the yoke device to accommodate excellent adjustment to the switch-point 2 and then held in such adjusted position by said lock nut 28. To positively lock the outer set of lock nuts on each 45 switch-point rod, the rod is provided with a plurality of aligned apertures 29 (Fig. 6), and in one of these apertures is placed a cotter pin 30 against the outer nut. As the rod 24 is adjusted within the sleeve of the yoke device, the lock nuts 50 can be adjusted longitudinally of the rod, and when the final adjustment is secured the nuts can be tightened with respect to the sleeve and then the cotter pin 30 placed in position.

It is to be understood that the connection at 12 55

of the bridal bar 4 and the connecting rod 11 is exposed to the view of the repair man, and any defect of the connection 12 will be readily discovered and can be easily repaired. Further, if a break should occur at the connection 12, which may be styled a joint or break in bridal bar or connections beyond 12, such a break will cause the two hooks 26 to drop down when switch is operated for inspection or otherwise which condition would be readily discovered by the repair man or others. On the other hand, my invention when hooks are replaced on switch point and switch reset, will hold the movable rail or switch-point against the stationary rail until switch can be spliced or repaired.

By reason of the plate 16 of the yoke device 15 being against the curved portion 12a, said plate 16 will be prevented from slipping forward. This construction will prevent hooks 26 from becoming disengaged from the flange 27.

I have shown the yoke device in the preferred form and have described the same in the foregoing specification, but modifications may be made involving an integral structure to the switch connecting rod, or it may be bolted, welded or cast.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In a switch mechanism of the class described, the combination of a movable switch-point, a bridal bar, means for fastening said bridal bar to said switch point, a connecting rod movably fastened to one end of said bridal bar, a yoke device on said connecting rod, said yoke device comprising a flat primary plate provided with integral sleeves at its ends, an auxiliary plate including a sleeve-like body and flat

flanges, said flat flanges against said primary plate between said sleeves, fastening means extending through said flat flanges and said primary plate, said connecting rod in said sleeve-like body, switch-point rods extending through the sleeves of said primary plate, said switch-point rods being screw threaded externally at said sleeves, lock nuts on said screw threads of said switch-point rods against the ends of said sleeves, and said switch-point rods provided with 10 hooks against said movable switch-point.

2. In a switch mechanism, the combination with a movable switch-point, of a bridal bar connecting to a primary plate, a yoke device on said connecting rod provided with a curved portion fastened to said 15 primary plate, a yoke device on said connecting rod against said curved portion, and means adjustably connecting said yoke device to said switch point.

3. In a switch mechanism, the combination 20 with a movable switch point, a bridal bar under said switch point, of a connecting rod provided with an upwardly curved end, means fastening said upwardly curved end to said bridal bar, a yoke device on said connecting rod against said 25 upwardly curved end, said yoke device comprising an upper plate bearing against the top of said connecting rod, adjustable switch-point rods engaging at one end said switch-point, and said upper plate of the yoke device provided with 30 means at its side-edges surrounding and supporting portions of said switch-point rods.

4. In a switch mechanism, the combination 35 with a movable switch-point, a bridal bar under said switch-point, of a connecting rod fastened to said bridal bar, a yoke device on said connecting rod, said yoke device comprising an upper primary plate resting flat upon the top of said connecting rod, said primary plate provided at its side-edges with sleeves, an auxiliary plate engaging the bottom surface of said 40 connecting rod and fastened to said primary plate between said sleeves, and switch-point rods engaging said switch-point and in said sleeves.

ANDREW M. RITCHIEY.
